UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Original application filed May 8, 1926, Serial No. 107,656. Divided and this application filed August 21, 1929. Serial No. 387,307.

My invention relates to a slicing machine and particularly to a slicing machine for slicing meat which shall be light, simple to manufacture, and easy to operate. One purpose is the provision of a slicing machine of the type described wherein the knife is entirely masked from the operator except along the arc of the knife where the slicing is effected. Another object is the provision of improved supporting and guiding means for the meat support. Another object is the provision of an improved gauge plate for controlling the thickness of the slice. Another object is the provision of improved adjustment means for the knife. Other objects will appear from time to time in the course of the specification and claims.

This application is a division of my pending application No. 107,656, filed May 20, 1926.

I illustrate my invention more or less diagrammatically in the accompanying drawings wherein—

Figure 1 is an end elevation with parts broken away;

Figure 2 is a plan view with parts in horizontal section;

Figure 3 is a front elevation with parts broken away;

Figure 4 is a section on the line 4—4 of Figure 3;

Figure 5 is a section on the line 5—5 of Figure 3; and

Figure 6 is a section on the line 6—6 of Figure 3.

Like parts are indicated by like symbols throughout the specification and drawings.

A generally indicates any suitable base frame or member provided for example with the anti-frictional and noise deadening studs or supports A¹.

Mounted on such base member is any suitable motor means herein shown as the motor B from which projects the motor shaft B¹ on which is the driving pulley B² adapted to

engage and drive the belt B³, herein shown as of triangular cross-section to engage the inclined faced channel B⁴ on the pulley B².

C is a knife supporting sleeve mounted upon the base A and including the shield portion C¹. It will be understood that the shield portion is continuous with or extends to the motor housing B and forms part of the general upwardly projecting housing or frame member C¹.

Mounted within the sleeve portion C is an inner sleeve D in which are mounted the ball bearing tracks D¹ to support the balls D² opposed to the inner tracks D³ on the knife shaft D⁴. D⁵ are locking nuts whereby to secure the knife shaft and roller bearing assembly together, the shaft D⁴ being enlarged as at D⁶ to engage the inner forward ball track D³. D⁷ is a channel pulley mounted on the shaft D⁴ adapted to receive about it the belt B³.

E is a knife disc proper secured to the shaft assembly for example by the screw E¹ and additionally secured to the pulley D⁷ for example by the screws E². The knife disc is shown as convex and is peripherally cut away or recessed on its hollow face, as at E⁴ to leave a peripheral portion E⁵ projecting somewhat forwardly from the face of the knife, the inner face of which is preferably, but not necessarily, cupped.

Mounted on the forward face of the frame member C¹ is the fixed guard plate H which may be of any suitable material. At its left edge, as shown in Figure 3, it is arcuately cut away as at H¹, the arcuate portion penetrating or seating closely within the peripheral channel E⁴ of the knife E the axis of the knife being slightly tilted in a horizontal plane from perpendicularity to the plate, as shown in Figure 2 to bring the edge of the knife forward into the position shown in such figure, generally in the plane of the guard plate H.

J is a frame or housing member upwardly

projecting from the opposite end of the base A. Mounted for rotation therewith is the control shaft J¹ upon the inner end of which is the worm J². Such shaft is controlled by the external handle J³ provided with indicating symbols as at J⁴ aligned with the opposed pointing member J⁵.

Pivoted to the vertical rock shafts J⁶ J⁷ within the housing J, are the levers or pairs 10 of levers K, K¹, at the outer end of each pair of which are pivoted the blocks or strips K², to which are secured any suitable gauge plate K³, the surface of which may be slightly convex or bowed, to conform to the cutting edge 15 of the knife E since the active cutting portion of the knife, due to the angle at which it is set, is not in a vertical plane but is slightly bowed forward. The right edge of said gauge plate K³, as shown in Figure 3, may be 20 arcuately formed, as at K⁴, generally concentrically with the arcuate portion H¹ of the fixed guard plate. The distance separating the opposed edges is, as shown in Figure 2, sufficient to permit the penetration therebetween of the peripheral portion E⁵ of the 25 knife E.

Secured to the rock shaft J⁶ is a segment worm gear K⁷ which meshes with and is driven by the worm J². A tension spring K⁸ 30 is secured at one end to a lug K⁹ on the frame J and at its opposite end to one of the pivoted blocks or strips K². This spring serves to hold the teeth in the segment K⁷ in close contact with the opposed teeth of the worm J².

Coiled around the upper part of the rock shaft J⁶ is a heavy spring K¹⁰, which is held under compression against the under side of one of the bearing lugs K¹¹ by the collar K¹² which is secured to the rock shaft J⁶. The resulting friction acts as a brake, and tends to hold the gauge plate K³ in any position in which it may be set by the operation of the handle J³.

The support of the gauge plate by means of 45 the parallel links K, K¹ not only provides for maintenance of parallelism of the active face of the gauge plate relative to the active face of the guard plate and relative to the line of movement of the carriage O, but also makes 50 possible the gradual widening of the throat between the active edge of the cutter and the forward edge of the gauge plate as that throat is deepened to provide for thicker slices, thereby providing the necessary 55 amount of clearance for the thicker slices. It will be readily understood that various well-known mechanical mountings for the gauge plate, by which uniform angular relation throughout adjustment may be maintained, 60 and by which the desired widening of the throat is attained as the throat is deepened, will readily suggest themselves to the average mechanic.

K⁶ is any suitable top or lid member extending from end to end of the slicing ma-

chine and adapted to be secured for example by the screws K⁶ to the housing J and the housing or frame C¹.

L is any suitable receiving plate for receiving the material sliced by the knife and L¹ is any suitable control switch for controlling the current to the motor of the motor housing B.

M is a track herein shown as of circular cross-section mounted for example on the supports M¹ upwardly projecting from the opposite ends of the base A. The ends of the track are enclosed by the sheathes M² apertured to permit the penetration of the bolts or screws M³ headed as at M⁴ and upwardly extending through the base A, the support members M¹, the sheathes M² and into the ends of the track M. Aligned beneath the track M is any suitable slide or rail M⁵ herein shown as of rectangular cross-section.

Mounted for movement along the track M and the rail M⁵ is any suitable carriage or supporting member herein shown as including a body portion O and a meat engaging member O¹. Such meat engaging member includes a broad face O² slightly inclined to the horizontal and a narrower face O³ sharply inclined to the horizontal the two being generally perpendicular to each other. Downwardly depending from the body portion O is an arm or slide O⁴ with a depending finger O⁵, which carries a bearing member O¹¹, adapted to engage one side of the slide M⁵. Movable secured to it is the finger member O⁶ in which is any suitable adjusting member herein shown as the screw O⁷ controlled by the lock nut O⁸. O⁹ are any suitable buffer members adapted to contact the posts M¹ at each end of the excursion of the carriage. O¹⁰ is any suitable handle for the manual movement of the carriage.

P is a meat face plate or pusher provided with the pins P¹ P¹ which penetrate opposed holes in the meat table support O. The pusher P is provided with a handle P² and carries on its front face pins P³ to engage the meat or other substance being sliced.

It will be realized that whereas I have illustrated and described a practical and operative device that nevertheless many changes may be made without departing from the spirit of my invention, and I therefore wish my drawings and description to be taken as in a broad sense illustrative and diagrammatic rather than as limiting me to my precise showing.

The use and operation of my invention are as follows:

I provide a generally vertical fixed guard plate, arcuately cut away to permit the penetration or the exposure of the rotary knife. The plane of the knife is tilted in order to bring the exposed edge generally into the plane or close to the plane of the forward face of the guard plate, the knife being hol-

lowed or sunk in order to permit its peripheral portion E^5 to extend forwardly beyond the body of the knife. Generally aligned with the fixed guard plate H is the adjustable gauge plate K^3 controlled by the worm J^2 which in turn is controlled by rotation of the handle J^3 . The gauge plate and guard plate are slightly bowed to conform to the curvature of the exposed knife edge. This bowing is particularly important in connection with the gauge plate but is also preferable in connection with the guard plate. Referring to Figure 3 it will be noted that the upper edge of the guard plate H projects forwardly somewhat as at H^{10} in order to permit the central portion, along the arc H^1 to penetrate the space in the knife. It is the central portion which is bowed, in order to conform to the contour of the cutting arc of the knife in the cutting plane. The forwardly offset portion H^{10} , and a corresponding lower offset portion concealed by the carriage O in Figure 3, are positioned above and below, respectively, that part of the guard plate which normally engages the work as the carriage is reciprocated. I have shown a fixed finger J^6 on the housing opposed to the symbols J^4 on the handle, but obviously any other practical means for controlling or indicating the necessary rotation of the worm may be employed. In response to rotation of the worm the link or lever K^1 is rotated and moves in unison with the gauge plate K^3 . The lever or link rotates necessarily in unison with the link K , the two being of like length between pivot points, the gauge K^3 always lying in a plane parallel with the plane of the guard plate H .

The material being cut is placed upon the carriage and is moved, for the cutting excursion, from left to right, as shown in Figures 2 and 3. The thickness of the slice is determined by the position of the gauge plate K^3 , the slice passes through the aperture between the edge of the knife and the gauge plate K^3 and drops upon the receiving plate L , from which it may be manually removed. With the gauge plate K^3 supported as herein shown, as the plate is moved backwardly from the cutting plane, in order to increase the thickness of the slice to be produced, the arcuate edge of the gauge plate draws readily away from the cutting edge, so that the throat between the gauge plate and the cutting edge is both deepened and widened, and, as the slice is thereby thickened, a relatively greater space is provided, through which the thickened slice may easily pass. This double recessive movement is the necessary result of the employment of the mounting herein shown, but obviously other means may be employed in order to impart to the gauge plate the combined rearward and lateral movement above described. An advantage of this disposition rests in the fact that the thickness of the slice increases

more readily than does the actual distance between the gauge plate and the plane of the knife and a smaller movement of the gauge plate is necessary.

As shown in Figures 2 and 5, the guard plate H is adjustable toward and away from the knife, for example by means of rotation of the threaded stud bolt Q screwed to the lugs Q^1 on the frame C^2 and secured by the screws Q^2 threaded into the stud bolt Q . The position of the plate H is preferably initially adjusted at the factory but further adjustment, if necessary, may easily be made by the operator. The knife shaft sleeve D being also longitudinally adjusted, it is possible easily and accurately to position knife and guard plate in the proper relation. The housing C^1 and the plate H between them entirely enclose the knife driving mechanism and the knife is exposed only along the cutting edge and only when the gauge plate is withdrawn. When the gauge plate is advanced forwardly to the position shown in full line in Figure 2 the entire edge of the knife is guarded or concealed.

I claim:

1. In a slicing machine, a guard plate, a rotary knife positioned on one side of said plate, the plane of the knife being tilted at a slight angle in relation to the plate, to bring a portion of the edge of said knife into the general plane of the plate, and a gauge plate, the face of said plate being bowed to conform to the contour of the edge of the tilted knife.

2. In a slicing machine a rotary knife, a guard plate overlying the major portion of said knife and leaving an arc of the edge thereof exposed, the exposed face of said guard plate lying at a slight angle to the plane of the edge of the knife, and a gauge plate having an arcuate end adjacent the edge of the knife, said gauge plate being bowed to approximate the exposed edge of the knife.

3. In a slicing machine a rotary knife, a guard plate overlying the major portion of said knife and leaving an arc of the edge thereof exposed, the exposed face of said guard plate lying at a slight angle to the plane of the edge of the knife, a gauge plate having an arcuate end adjacent the edge of the knife, said gauge plate being bowed to approximate the exposed edge of the knife, and means by which the throat between said gauge plate and knife may be varied as to depth.

4. In a slicing machine a rotary knife, a guard plate overlying the major portion of said knife and leaving an arc of the edge thereof exposed, the exposed face of said guard plate lying at a slight angle to the plane of the edge of the knife, a gauge plate having an arcuate end adjacent the edge of the knife, said gauge plate being bowed to

approximate the exposed edge of the knife and means by which the throat between said gauge plate and knife may be varied as to depth and width.

5. In a slicing machine a rotary knife, a guard plate overlying the major portion of said knife and leaving an arc of the edge thereof exposed, the exposed face of said guard plate lying at a slight angle to the plane of the edge of the knife, a gauge plate having an arcuate end adjacent the edge of the knife, said gauge plate being bowed to approximate the exposed edge of the knife and means for adjusting the gauge plate relatively to and in parallelism with the guard plate.

6. In a slicing machine a rotary knife, a guard plate overlying the major portion of said knife and leaving an arc of the edge thereof exposed, the exposed face of said guard plate lying at a slight angle to the plane of the edge of the knife, a gauge plate having an arcuate end adjacent the edge of the knife, said gauge plate being bowed to approximate the exposed edge of the knife, and means by which the throat between said gauge plate and knife may be varied simultaneously as to depth and throat, and the gauge plate maintained in parallelism with the guard plate.

7. In a slicing machine, a guard plate, a rotary knife positioned on one side of said plate, the plane of the knife being tilted at a slight angle in relation to the plate, means for driving the knife, and means for adjusting the plate toward and away from the knife, including in part a frame structure upon which knife and plate are mounted, securing members for said plate, adapted to penetrate said frame, and spacing members adjustable along said securing members against which said plate is adapted to abut.

8. In a slicing machine a rotary cutter, a guard plate overlying the major portion of the face of said cutter but leaving an arc of the edge of said cutter exposed, said guard plate having an exposed face lying at a small angle to the plane of the edge of the knife, means by which there may be a relative adjustment between the plane of the knife edge and the face of the guard plate, a gauge plate arranged beyond the exposed edge of the knife, and means by which there may be a relative adjustment between the gauge plate and knife edge to vary the depth of the throat of the guard plate and gauge plate.

9. In a slicing machine a rotary cutter, a guard plate overlying the major portion of the face of said cutter but leaving an arc of the edge of said cutter exposed, said guard plate having an exposed face lying at a small angle to the plane of the edge of the knife, means by which there may be a relative adjustment between the plane of the

knife edge and the face of the guard plate, a gauge plate arranged beyond the exposed edge of the knife, and means by which there may be a relative adjustment between the gauge plate and knife edge to vary the depth of the throat and maintain parallelism of the guard plate and gauge plate.

10. In a slicing machine, a rotary knife and means for rotating it, the axis of rotation of said knife lying in a generally horizontal plane, a guard plate positioned forwardly of said knife and lying in a generally vertical plane, the axis of said knife being tilted to bring the cutting arc of said knife into the plane of said guard plate, a gauge plate positioned in a plane generally parallel with the plane of said guard plate, a carriage adapted to support the material being sliced, and means for guiding said carriage along a path generally parallel with the faces of the gauge plate and the guard plate.

11. In a slicing machine, a rotary knife and means for rotating it, a guard plate positioned forwardly of said knife, the axis of said knife being tilted to bring the cutting arc of said knife into the plane of said guard plate, a gauge plate positioned in a plane generally parallel with the plane of said guard plate, a carriage adapted to underlie and support the material being sliced, and means for guiding said carriage along a path generally parallel with the faces of the gauge plate and the guard plate.

12. In a slicing machine, a rotary knife and means for rotating it, the axis of rotation of said knife lying in a generally horizontal plane, a guard plate positioned forwardly of said knife and lying in a generally vertical plane, the axis of said knife being tilted to bring the cutting arc of said knife into the plane of said guard plate, a gauge plate positioned in a plane generally parallel with the plane of said guard plate, a carriage adapted to support the material being sliced, and means for guiding said carriage along a path generally parallel with the faces of the gauge plate and the guard plate, and means for manually moving the material being sliced toward the gauge plate, and for moving the material and carriage past the cutting edge of the knife.

13. In a slicing machine, a guard plate, a rotary knife positioned on one side of said plate, the plane of the knife being tilted at a slight angle in relation to the plate, to bring a portion of the edge of the knife into the general plane of the plate, and a gauge plate, the face of the guard plate being bowed to conform to the contour of the edge of the tilted knife.

14. In a slicing machine, a guard plate, a rotary knife positioned on one side of said plate, the plane of the knife being tilted at a slight angle in relation to the plate, to bring the portion of the edge of the knife into the

general plane of the plate, and a gauge plate, the faces of the guard and gauge plates being bowed.

15. In a slicing machine, a guard plate, a rotary knife positioned on one side of said plate, the plane of the knife being tilted at a slight angle in relation to the plate, to bring a portion of the edge of said knife into the general plane of the plate, the knife being formed with a central concavity surrounded by a peripheral rim forwardly projecting therefrom, the guard plate being offset at top and bottom to clear said rim, the intermediate portion of the guard plate penetrating said concavity and being bowed to conform generally to the contour of the edge of the knife.

16. In a slicing machine, a rotary knife and means for rotating it, the axis of rotation of said knife lying in a generally horizontal plane, a guard plate positioned forwardly of said knife and lying in a generally vertical plane, the axis of said knife being tilted to bring the cutting arc of said knife into the plane of said guard plate, a gauge plate positioned in a plane generally parallel with the plane of said guard plate, a carriage adapted to support the material being sliced, and means for guiding said carriage along a path generally parallel with the faces of the gauge plate and the guard plate, the knife being formed with a central concavity and surrounding rim, the guard plate entering and conforming to the arcuate edge of the concavity and being offset to clear said rim.

17. In a slicing machine, a rotary knife and means for rotating it, a guard plate positioned forwardly of said knife, the axis of said knife being tilted to bring the cutting arc of said knife into the plane of said guard plate, a gauge plate positioned in a plane generally parallel with the plane of said guard plate, a carriage adapted to underlie and support the material being sliced, and means for guiding said carriage along a path generally parallel with the faces of the gauge plate and the guard plate, the knife being formed with a central concavity and surrounding rim, the guard plate entering and conforming to the arcuate edge of the concavity and being offset to clear said rim.

18. In a slicing machine, a rotary knife and means for rotating it, the axis of rotation of said knife lying in a generally horizontal plane, a guard plate positioned forwardly of said knife and lying in a generally vertical plane, the axis of said knife being tilted to bring the cutting arc of said knife into the plane of said guard plate, a gauge plate positioned in a plane generally parallel with the plane of said guard plate, a carriage adapted to support the material being sliced, and means for guiding said carriage along a path generally parallel with the faces of the gauge plate and the guard plate, and means for

manually moving the material being sliced toward the gauge plate, and for moving the material and carriage past the cutting edge of the knife, the knife being formed with a central concavity and surrounding rim, the guard plate entering and conforming to the arcuate edge of the concavity and being offset to clear said rim.

Signed at Indianapolis, county of Marion, and State of Indiana, this 16th day of July, 1929.

WILLIAM J. CAMPBELL.
